UNITED STATES PATENT OFFICE.

HORACE BRIDGE, OF CHICAGO, ILLINOIS.

CAR-COUPING.

SPECIFICATION forming part of Letters Patent No. 519,231, dated May 1, 1894.

Application filed September 15, 1893. Serial No. 485,630. (No model.)

To all whom it may concern:

Be it known that I, HORACE BRIDGE, a citizen of the United States, residing at Chicago, in the county of Cook and State of Illinois, have invented a Car-Coupler and Draw-Bar, of which the following is a specification.

My invention relates to improvements in car couplings, in which the coupling pin acts automatically upon the introduction of the coupling link in common use and in which the operation of uncoupling is easily and safely performed from the side or top of the car, the pin being retained in the drawhead by a mechanism to be explained.

Other improvements consist in the introduction of a movable link slide, so that the link may be introduced entirely within the drawhead upon meeting a solid obstruction, and returned to the coupling position upon the removal of the obstruction; also in the posterior end of the drawbar being occluded by a movable block, perforated vertically and horizontally for the passage of bolts.

The objects of my invention are as follows:—to afford the simplest form of coupling consistent with the conditions required by railway car service, *i. e.*, strength to endure great tension, solidity and firmness to withstand concussion, facility in operation, &c; to supply a means for the automatic coupling of cars; to enable employés to uncouple from the side or top of cars; to furnish an efficient automatic coupling apparatus of such construction, that its cost shall be but little in excess of the ordinary non-automatic couplers, and that the expense of operating it and repairing it may be reduced to the minimum. I attain these objects by the mechanism illustrated in the accompanying drawings.

Figure 1 is a vertical section of the apparatus in the median line, with the coupling pin in locked position; Fig. 2, a view in perspective of the same. Figs. 3, 4, 5 and 6, views of the coupling pin and other parts required in the construction of this apparatus.

Similar letters refer to similar parts in the different figures.

The words anterior, posterior, superior and inferior apply to the apparatus and its parts as they appear in Fig. 1.

The drawhead, "B," has an opening ante-

riorly for the introduction of the link, with symmetrical sides, but the lower surface, "q," extending farther posteriorly than the upper 55 surface, "j," and farther downward from the central point of the link passage than the upper surface, "j," extends upward from the same point, so that, when the link rests on the floor of the passage in the horizontal position for coupling, it is equidistant from the anterior edges at the top and bottom of the opening. This opening is flaring for the guidance of the link to the center of the passage. Superiorly there is a passage, "a," 60 which extends from the upper surface of the drawhead downward and forward into the link passage at an angle approximating thirty degrees with the perpendicular. It is enlarged by a recess, "b," anteriorly, also by a space, "c," 65 posteriorly and superiorly, for the requisite automatic movements of the coupling pin; laterally also the walls of the passage, "a," are somewhat excavated, partially indicated by, "z," to provide for the possibility of the point 70 of the coupling pin being bent sidewise and to permit its withdrawal from the drawhead. On the floor of the link passage there is a socket, "d," to receive the point of the coupling pin, "s." Its anterior surface, "d," is inclined 75 from below upward and forward at an angle approximating forty-five degrees with the perpendicular. Posterior to the socket, "d," is the continuation anteriorly of the drawbar passage, "i," terminated by the stop, "k," 80 which is a plane vertical surface at right angles to the axis of the drawbar, rising to the floor of the link passage, and may be located at a variable distance from the socket, "d." The anterior surfaces of the passage, "a," and 85 of the socket, "d," (a' and d') being inclined forward to a common point hold the coupling pin the more firmly the greater the traction exerted upon it by the link, and when traction ceases leave the pin perfectly free for 90 withdrawal. The link passage of the drawhead is continued into the drawbar to permit the entire penetration of the link within the drawbar. Externally, on the sides of the drawhead and inferiorly, are ribs to 95 strengthen the lips of the anterior opening. The posterior vertical surface, "g," serves as a stop to the introduction of the drawbar, when the resistance of the drawbar springs.

has been taken up. No buffers are required with the use of this apparatus.

The drawbar, "A," is adapted anteriorly to the complete introduction of the link within the drawhead. It is hollow throughout its entire length, the passage being square, with rounded corners, and extending about half way through the drawhead. In this passage, "i," the link slide, "C," operates; it is terminated anteriorly by the stop, "k," which may, or may not, be located at a point sufficiently anterior to allow the link slide to hold the link in apposition with the coupling pin. In the posterior end of the body are lateral and vertical holes, through which pass bolts, "J," which secure the block, "D," and the clamp, "I." The followers, "G," the clamp, "I," and the two drawbar springs, not shown, are like those in common use and need no description.

The occluding block, "D," is nearly cubical in form; it has two vertical and lateral perforations, "l," for the bolts, "J," corresponding to two similar perforations in the end of the drawbar above and below; also a horizontal one, "m," for the bolt, "H." The block serves as a base for the spring, which operates the link slide, "C;" it solidly occludes the end of the drawbar and holds the bolt, "H," which together with the clamp, "I," holds the drawbar springs in position and withstands the force of traction.

The link slide, "C," is a spring actuated, chambered block adapted to antero-posterior movements in the passage of the drawbar, "i," and to fit the same. It has a squared front end provided with a link seat, or notch, "f." The lower part of its anterior surface is a vertical plane at right angles to the axis of the link slide, of equal dimensions with the stop, "k," and adapted to meet the same, thus checking the anterior movement of the link slide.

The link seat or notch, "f," is an excavation; its deepest point is distant in a vertical line from the floor of the link passage, when the link slide is in position, one half the thickness of the link. Below this point the surface is concave, approximating a quarter circle, and extends to the superior edge of the vertical plane above described. Above this point the surface extends in the line of the circle forty-five degrees; it then continues convex describing the segment of a circle having for its center a point situated in a straight line, passing through the center and last point of the last segment described, and finally becomes merged in the front end of the block at or near its superior edge. Against this surface, "f," the end of the link, resting on the floor of the passage, is applied, and the link retained in the horizontal position for coupling; also when the contiguous drawhead requires the deflection downward of the free end of the link and the consequent rising of the engaged end to effect coupling, this move-

ment is permitted by the requisite retirement of the link slide as the link end slides upward. The cylindrical chamber, "x," is adapted to receive the anterior end of the link 70 slide spring, Fig. 6. Its walls, when in coupling position extend posteriorly just beyond the inner end of the link passage, closing the interior of the drawbar against the weather, dust, &c., yet allowing sufficient retrocession 75 of the link slide, when pushed by the link, as to admit of the entire introduction of the link within the drawhead; they are also of sufficient length to insure the antero-posterior movements of the link slide with the 80 minimum of friction. Link slide and spring are of large size to insure efficiency, and introduced by the posterior end of the drawbar.

Fig. 5 is the coupling pin. The posterior 85 and anterior surfaces of the body, "o and p," are rounded to run smoothly in the passage, "a," Fig. 1. Superiorly is the half link, "n," firmly embedded, to which a chain, or other device, can be attached, so that the pin can 90 be drawn upward in the operation of uncoupling. The point of the pin, "s," is rounded and wedge shaped; its posterior surface, "t," is nearly vertical; its anterior surface, "v," is inclined from above downward and 95 backward at an angle with the perpendicular approximating forty-five degrees. The pin and its containing passages are so fashioned, that the entering link pushes it up with only the resistance of gravity, and the 100 minimum of resistance from friction to be overcome, its point being carried in the posterior direction only the fractional part of an inch, and then upon striking the point, "u," being thrown upward, as is permitted by the recess, "b," and space, "c," Fig. 1, the pin falling to the locked position, when the link has passed. The pin cannot be thrown out of the drawhead by the entering link, nor pulled out by its attachments at the side or 105 top of the car, but may easily be removed by hand.

The link slide spring operates in the spaces, "x and i," Fig. 1, and holds the link slide in coupling position. It is strong enough to 110 push the link into the connecting drawhead, and to force up its coupling pin; in case, however, the link meets a solid obstruction, it will force back the link slide, until it, the link, is entirely within the drawhead unbent and 115 unbroken.

The operation of coupling, when cars furnished with this apparatus come together is as follows:—The link is pushed back in one draw head, until the engaged end rests in the seat, "f," and remains in the horizontal position on the floor of the link passage. The coupling pins in both drawheads are held in the locked position, as in Fig. 1. As the cars come together the free point of the link held in one drawhead is deflected to the center of the opening in the other drawhead by its flar-

ing surfaces; it strikes the pin forcing it upward and backward. The link having passed the pin falls to the locked position.

Operation of uncoupling: The coupling pin 5 may be withdrawn by means of a crank rod running to either side of the car, or by a rod running to the top of the car, both attached by a short chain to the coupling pin; or by chain and pulley; or by other device.

Having thus fully described my invention, 10 what I claim as new, and desire to secure by Letters Patent, is—

1. The combination in a car coupling of a drawhead having a flaring opening anteriorly with symmetrical sides, but with the lower surface extending farther downward than the upper surface extends upward, from the central point of the link passage, and also extending farther backward; having an oblique 15 passage, "a," extending from the superior surface of the head downward and forward at an angle with the perpendicular approximating thirty degrees, with the recess, "b," anteriorly, the space, "c," posteriorly, and the 20 depressions, "z," laterally; having the depression or socket, "d," in the floor of the link passage, with its anterior surface "d'," inclined from below upward and forward at an angle with the perpendicular approximating 25 forty-five degrees; having a link passage con-

tinued into the drawbar of sufficient length to admit of the entire introduction of the link within the drawhead, and a link slide passage, "i," terminated anteriorly by the stop, "k," 35 extending through the drawbar, being rectangular and provided with rounded corners and at its rear end with two lateral and vertical holes as described.

2. The combination in a car coupling of an automatic coupling pin, the body being flat 40 with rounded anterior and posterior surfaces, "p" and "o," the latter being much shorter than the former: the point being wedge shaped, its posterior surface, "t," rounded and vertical, its anterior surface, "v," inclined 45 from above downward and backward at an angle with the perpendicular approximating forty-five degrees, with a half link, "n," embedded in the upper part of its superior surface. 50

3. The combination in a car coupling of an occluding block, "D," distinguished by being perforated with two lateral and vertical holes, and one horizontal hole, for the passage of bolts substantially as and for the purpose set forth. 55
